UNITED STATES PATENT OFFICE

166,903

ASH TRAY

Boris Blecher, Philadelphia, Pa.

Application February 15, 1952, Serial No. 18,535

Term of patent 14 years

(Cl. D85—2)

To all whom it may concern:

Be it known that I, Boris Blecher, a citizen of the United States and a resident of Philadelphia, county of Philadelphia, State of Pennsylvania, have invented a new, original, and ornamental Design for an Ash Tray, of which the following is a specification, reference being had to the accompanying drawings, forming a part thereof, wherein:

Figure 1 is a plan view of the ash tray showing my new design;

Figure 2 is a side edge elevational view thereof as viewed from the line 2—2 of Figure 1;

Figure 3 is a transverse sectional view thereof as taken along the line 3—3 of Figure 1; and

Figure 4 is a transverse sectional view as taken along the line 4—4 of Figure 1.

I claim:

The ornamental design for an ash tray, as shown.

BORIS BLECHER.
